UNITED STATES PATENT OFFICE.

RICHARD OETTINGER, OF MUNICH, GERMANY.

CASTING APPARATUS.

Application filed January 12, 1928, Serial No. 246,194, and in Germany September 23, 1926.

- The casting apparatus herein described has for its purpose, and achieves the complete filling up of casting moulds, without any loss of material, and the attaining of an excellent homogeneity of certain alloys of gold in the direct casting process. Therefore it is particularly suited for casting work pertaining to dental surgery, jewelry, trinkets, etc.
- 10 The new apparatus makes it possible that in casting, centrifugal force, as well as air and steam pressure, can operate at the same time.
- 15 The invention comprises a lid sliding easily on two rods holding the pan, said lid covering the pan and the cuvette, placed in the middle of the pan in the manner of a box-cover, immediately after the casting process is started; convenient means are provided
- 20 for holding the lid up near the handle before the casting.

The accompanying drawings show by way of example two forms of execution of a new casting apparatus according to the invention.

- 25 Figure 1 is a view of the first form of execution before the casting,
 Figure 2 after the casting;
 Figure 3 is a vertical section of the apparatus.
- 30 Figure 4 is an enlarged view of a part of the same.
 Figure 5 is a view of the casting cuvette.
 Figure 6 shows the second form of execution of the apparatus.
- 35 Figure 7 is an enlarged view of a part of the same, partly in section.

The first form of execution (Figs. 1-5) may be used in the fabrication of smaller objects, such as inlays, bridgework, or smaller plates in dental surgery, and for smaller ornaments generally.

40 The second form (Figs. 6 and 7) may be used in the fabrication of large plates of teeth or larger trinkets.

45 The construction of the casting apparatus has retained the outer frame of the well-known casting-sling, viz, a pan 1, held by two rods 2, connected by a bow 3. A heavy wire 4 is jointed on one end to the middle

of this bow and on the other end to the handle 5, by which the apparatus can be rotated in the usual way. So far the construction corresponds to the well-known sling.

According to the invention, a cover 6 has 55 been interposed as a falling lid between pan 1 and bow 3. The aperture of lid 6 is turned towards the aperture of pan 1, the diameter of lid 6 being smaller than that of pan 1. Small eyelets or short tubes 7 are fitted to 60 the side of lid 6 and a small hook 8 to the top on the outside of the same, corresponding to a second hook 9, attached to bow 3. Between these two small hooks 8 and 9 a spring or small india-rubber ring is fixed, 65 holding the lid 6 near the bow 3. The apparatus is expediently provided with two lids of different sizes, so that a smaller or larger lid can be used as required.

The changing and inserting of the larger 70 or smaller lids between bow and pan is made possible by the feature that the upper part of the sling can be taken apart, as Figure 4 illustrates on a larger scale. Figure 4 shows the end of the threaded rod 2, of smaller diameter for insertion into bow 3, which can be secured by a screw socket 11.

In the casting process lid 6 falls onto pan 1 by rotating the apparatus on account of the centrifugal force and fits tightly over the 75 pan box-fashion. The rubber ring breaks during the casting. Figure 3 shows that asbestos packings 12 which are fitted into the top of lid 6, which rests on the upper rim of the cuvette 13, close the latter. Figure 3 80 shows further that two pins 14 are attached to the pan.

Casting cuvettes of special shape serve as accessories for the casting apparatus (Fig. 5). The mould can have, for instance, the 85 following form. A short tube 13 is fixed to a flange 15 containing two bores 16, so that the cuvette can be inserted over said pins fixed to the pan, and fits securely. The cuvettes are in stock in round and oval shape and in 90 all necessary heights and diameters.

According to the second form of execution (Figs. 6 and 7) an axle 19 is screwed to a table 18 (or attached to a wall) by means of a holding device 17. Axle 19 is contained in a tube 100

19^a, to which a lever 20 is attached, which is provided with a handle 21, as well as with a slideable counterweight 22. Opposite to the lever 20 two heavy iron rods 23 are attached.

5 Furthermore a second handle 24 is attached to the tube 19^a containing the axle 19. Bow 3 connecting the two carrying rods 2 is swingably attached to the ends of rod 23, said axle 3 being easily detachable. For this purpose 10 pins 26 can be inserted through cross-bores 25 of rods 23 into axial bores 27 on the ends of axle 3, thereby holding the latter, as illustrated in Fig. 7 on an enlarged scale. The securing of the pins 26 is accomplished by 15 clamping-screws 28, which are inserted in threaded bores 29 of the ends of the iron rods 23.

The other parts of this casting apparatus are constructed in the same way as those of 20 the first form, illustrated in Figs. 1-5.

Both forms of casting apparatus described herein show important improvements in comparison to the casting apparatus, previously in use. The new apparatus 25 combines the rotation system with the pressure system. Both, centrifugal force and pressure, are put into use at the same time, the centrifugal force being generated by the rotation of the sling-apparatus, and the pressure 30 by the falling of the lid during the rotation of the sling.

A further improvement of the invention consists in that the apparatus makes it possible to obtain homogeneous gold alloys, 35 which do not corrode nor change their colour in the mouth, on being used for dental purposes, and which contain only very few holes, so that a cast for dental purposes possesses the necessary resistance against the chewing 40 pressure.

The essential part of the construction, the provision of a falling lid, brings it about that the cuvette is entirely closed by the box-like combination of the falling lid with the pan, 45 thereby preventing the air from entering the cuvette, thus lowering the high temperature of the cuvette slowly and regularly.

The result of this is, that the molten alloy is enabled to form crystals of homogeneous 50 structure.

The pressure caused by the falling of the lid is used in different ways according to the use of gold alloys. For gold-alloys the air-pressure alone is made use of, which is originated by the falling of the lid onto the pan.

In slowly flowing metals a steam-pressure is employed. In this case the asbestos packing in the top of the lid is moistened. When the cover falls onto the hot cuvette, steam 60 is produced, the pressure of which acts in addition to the centrifugal force.

What is claimed as new is:—

1. In a casting device, the combination with a flask having an open top adapted to 65 receive molten material, and means for cen-

trifugalizing said flask to cause said material to flow downwardly from said top; of a lateral flange on the flask bottom, and means for automatically causing a closure of said top after said centrifugalization is initiated; 70 said last-named means including a cover mounted for movement in a radial direction, said cover comprising a top wall and depending side walls adapted to engage with said flange. 75

2. In a casting device, the combination with a pan, a flask adapted to rest thereon and having an open top for the reception of molten material, and means for centrifugalizing said pan and flask to cause said material 80 to flow downwardly from said top; of means for securing said flask to the pan in a predetermined position, said means comprising pins on said pan and a complementary bored flanged on said flask adapted to engage over 85 said pins.

3. In a casting device, the combination with a sling comprising a pair of rods, a bow at one end and a pan at the other, a flask adapted to rest on said pan and having 90 an open top adapted to receive molten material, and means for centrifugalizing said sling to cause said material to flow downwardly from said top; of means for automatically causing a closure of said top after said centrifugalization is initiated; said last-named means comprising a cover slidably mounted on said rods over said pan. 95

4. In a casting device, the combination with a sling comprising a pair of rods, a bow at one end and a pan at the other, a flask adapted to rest on said pan and having an open top adapted to receive molten material, and means for centrifugalizing said sling to cause said material to flow downwardly from 100 said top; of means for automatically causing a closure of said top after said centrifugalization is initiated; said last-named means comprising a cover slidably mounted on said rods over said pan, and means yieldable under centrifugal force for normally holding said cover off of said flask, said yieldable means comprising an element extending 105 between said cover and said bow. 110

5. In a casting device, the combination with a sling comprising a pair of rods, a bow at one end and a pan at the other, a flask adapted to rest on said pan and having an open top adapted to receive molten material, and means for centrifugalizing said sling to cause 115 said material to flow downwardly from said top; of a cover slidably mounted on said rods, and means for removably securing said bow to said rods, whereby the cover may be withdrawn entirely from said rods. 120

In testimony whereof I hereunto affix my signature.

RICHARD OETTINGER.
